UNITED STATES PATENT OFFICE.

ERNST R. GIFFHORN, OF BROOKLYN, NEW YORK.

WAVE-MOTOR.

1,071,225.

Specification of Letters Patent. Patented Aug. 26, 1913.

Application filed February 21, 1913. Serial No. 749,761.

To all whom it may concern:

Be it known that I, ERNST R. GIFFHORN, a citizen of the United States, residing at Brooklyn, county of Kings, and State of New York, have invented a new and Improved Wave-Motor, of which the following is a specification.

This invention relates to a motor for effectively utilizing the force of the ocean waves, the construction being such that the motor automatically participates in the periodic flood and ebb of the waters and that its operation is continuously maintained even after a wave has expended its force and 15 while the water is receding prior to the arrival of a succeeding wave.

In the accompanying drawing: Figure 1 is a plan view of my improved wave motor; Fig. 2 a cross section on line 2—2, Fig. 3; 20 Fig. 3 a vertical section on a reduced scale on line 3—3, Fig. 1, and Fig. 4 a detail of the bucket tilting means.

The wave motor comprises essentially a pair of floats or pontoons 10 which support 25 an intermediate casing 11 by means of a plurality of inclined braces 12. Casing 11 comprises essentially a pair of parallel side plates 13 and is guided in its vertical tidal movement along a plurality of stationary 30 posts 14, Fig. 1 showing four of such posts. The latter are provided with rails 15 engaged by flanged wheels 16 which are fast on transverse shafts 17 journaled in bearings 18 of side plates 13. Within casing 11 is 35 journaled an overshot bucket wheel 19 mounted on a transverse shaft 20 which is supported in suitable bearings 21, 22 secured to side plates 13 and pontoons 10 respectively. A crank 23 formed on shaft 20 near 40 one end thereof between the bearings 22 carried by one of the pontoons 10 is engaged by the pitman 24 of a pump, compressor or other motion utilizing device 25 to be driven by bucket wheel 19. The latter 45 is provided with a multitude of transversely extending peripheral pockets 26 which may be closed at their ends as at 27. Each pocket is formed with a radially extending straight wall 28 and with a curved wall 29, 50 struck from the outer end of wall 28.

At the outer end of each straight wall 28, there is located a transverse arbor 30 journaled in bearings 31 of wheel 19. Each arbor 30 passes tightly through the tubular hub or knuckle 32 of an oscillatable bucket 33 which is of a shape and size to be snugly

housed within pocket 26. That is to say, each bucket is of sector shape, corresponding to the shape of pocket 26 and has a radial back 34, a radial open front 35 and an arched peripheral body 36, struck from axis of arbor 30.

It will be seen that by the means described, each pocket is by the rotation of wheel 19, caused to freely swing with its arbor 30 through an angle of about 180 degrees, the outward movement of the buckets being checked by means of radial partitions 37 formed on wheel 19 between pockets 26.

Wheel 19 is by the pontoons 10 held at such an elevation that it is submerged with its lower portion say up to the line 38—38, which represents the main water level, while its upper portion protrudes above such level. Means are provided for directing the waves to the exposed upper portion of wheel 19; so as to here discharge a substantial body of water and fill the uppermost buckets. These means comprise a trough 39 secured to casing 11 at a distance above wheel 19 and having a lower transverse discharge slot 40 located slightly beyond the wheel axis at the descending side of the wheel. The sea side of this trough is prolonged downward to form an inclined deflecting plate 41, which extends with its lower end to about the water level, and thus guides the wave crests into the trough. In this way, the latter will constitute a catch basin, within which a body of water will be constantly accumulated to flow in a continuous stream into the top buckets and cause a corresponding turning of the wheel. The power of this stream is augmented by the force of the waves themselves, which are entrapped from time to time by means of an inclined guide plate 42 secured to casing 11, some distance below plate 41. Between plates 41, 42, there is thus formed an ascending chute 43 through which the incoming waves will be deflected toward the top of heel 19 to be here discharged through an outlet 44. A third force which will tend to turn the wheel is formed by the undertow current which will act against the lower submerged buckets on the land side of the device, upon the recession of the waves.

On the rising side of wheel 19, there is secured to casing 11, a submerged baffle plate 45 having a bent portion 45^a which is arranged concentric to the wheel, and protects the lower rising buckets against the water motion. These rising buckets will grad-

ually swing back into their pockets, the water being discharged therefrom as soon as the buckets have been carried above the water level. When a bucket has thus been 5 carried to near the top of the wheel, it will have swung completely into its pocket from which position it must be mechanically dislodged, so that it will project beyond the wheel periphery and present its open side 10 to the water descending through outlets 35 and 44. The means for oscillating the buckets comprise a short arched rack 46 carried by each side plate 13 near the rising top of wheel 19 and arranged concentrically 15 to shaft 20. Each arbor 30 carries at its end a pinion 47 adapted to engage said rack, so that when the bucket arrives at the point mentioned, its pinions will become temporarily engaged by the racks, so that it will be 20 swung outward through an angle of 180 degrees and rest with its back 34 upon partition 37. In this way, the bucket will be 25 swung clear of the wheel and thus expose its open side 35 to a fresh charge of descending energizing water.

It will be seen that my improved wave motor will fully utilize the force of the waves breaking at a sea shore and convert the same into stored up energy in a simple 30 and practical manner.

I claim:

1. A wave motor comprising a float, a horizontally disposed shaft rotatably supported thereby, an overshot wheel mounted 35 on said shaft, a plurality of buckets hingedly connected to said wheel, means also supported by the float and located in proximity to the top of the wheel at the rising side thereof for swinging the buckets outward, 40 and means for directing the waves toward the outwardly swung buckets.

2. A wave motor comprising a float, a horizontally disposed shaft rotatably supported thereby, an overshot wheel mounted 45 on said shaft, a plurality of buckets hingedly connected to said wheel, means also supported by the float and located in proximity to the top of the wheel at the rising side thereof for swinging the buckets outward, a 50 catch basin having an outlet above the wheel, and means for directing the waves partly toward the outwardly swung buckets and partly to the catch basin.

3. A wave motor comprising a pontoon, a casing supported thereon, means for guiding 55 the casing, an overshot wheel having peripheral pockets and a shaft which is journaled in the casing, a power-supplying device operated by the shaft, oscillatable buckets hinged to the wheel and adapted to engage 60 the pockets thereof, and means for swinging said buckets out of said pockets at the rising side of the wheel.

4. A wave motor comprising a pontoon, a casing supported thereon, means for guiding 65 the casing, an overshot wheel having peripheral pockets and a shaft which is journaled in the casing, a power-supplying device operated by the shaft, oscillatable buckets hinged to the wheel and adapted to engage 70 the pockets thereof, means for swinging said buckets out of said pockets at the rising side of the wheel, and a catch basin secured to the casing and having a discharge slot above the wheel. 75

5. A wave motor comprising a pontoon, a casing supported thereon, means for guiding the casing, an overshot wheel having peripheral pockets and a shaft which is journaled 80 in the casing, a power-supplying device operated by the shaft, oscillatable buckets hinged to the wheel and adapted to engage the pockets thereof, means for swinging said buckets out of said pockets at the rising side 85 of the wheel, a slotted catch basin secured to the casing above the wheel and having an inclined wave deflecting plate, and an inclined guide plate located a distance below said deflecting plate to form an intervening chute having a discharge opening in proximity to the top of the wheel. 90

6. A wave motor comprising a casing, supporting pontoons for said casing, an overshot wheel journaled in the casing and having transversely extending peripheral 95 pockets, sector-shaped buckets adapted to engage said pockets and having shafts that are journaled in the wheel, pinions carried by the shafts, and curved racks on the casing that are adapted to be engaged by the 100 pinions for a limited period during each rotation of the wheel.

ERNST R. GIFFHORN.
